UNITED STATES PATENT OFFICE.

NORMAN MARSHALL, OF NEWTON, MASSACHUSETTS, ASSIGNOR TO MARSHALL-SANDERS COMPANY, OF BOSTON, MASSACHUSETTS, A CORPORATION OF MAINE.

PLUG AND RECEPTACLE.

SPECIFICATION forming part of Letters Patent No. 714,928, dated December 2, 1902.

Application filed November 7, 1900. Serial No. 35,775. (No model.)

To all whom it may concern:

Be it known that I, NORMAN MARSHALL, a citizen of the United States, residing at Newton, in the county of Middlesex, State of Massachusetts, have invented a new and useful Electric Coupling or Plug and Receptacle, of which the following is a specification.

My invention relates to improvements in couplings for electric circuits designed to make temporary connections or taps to permanent circuits, commonly known as "plugs" and "receptacles;" and the object of my invention is to provide a strong, compact, easily-wired, and cheap coupling.

I attain these objects by the mechanism illustrated in the accompanying drawings, in which—

Figure 1 is a sectional view of my fusible coupling with the plug inserted and circuit closed. Fig. 2 is a plan view of the inside portion of the cap or plug, showing the leading-in wires, contact-plugs, and fuses. Fig. 3 is a sectional view of the coupling without fuses. Fig. 4 is a view of the inside of the cap, showing the clips which hold the leading-in wires of the temporary tap, plugs, and holes for leading-in cable. Fig. 5 is a plan of the receptacle with the lid up and cap removed.

Similar letters refer to similar parts throughout the several figures.

The cap A, Figs. 1 and 2, preferably made of porcelain, has a recess F, upon the bottom of which are borne the coupling-pins H H', with which are connected the fuse-wire screws O O', and from these screws lead the fuses L L' to the wire-binding clips R R', to which the cable or wires G are attached.

B, Figs. 1 and 3, is a body, of insulating material, preferably porcelain, with shouldered recesses for the coupling-sleeves S S' and slots upon the sides for the wire-binding screws T T'. The metal coupling-sleeves S S' are drilled out at their upper ends and split, so as to clamp the plugs H H', carried by the cap. The lower ends are drilled to receive the wires K K' and tapped laterally for the binding-screws T T'. These sleeves are shouldered, as shown, near the lower end to fit a corresponding shoulder on the porcelain and

the reduced portion threaded at I I', so that when the nuts J J' are screwed on the sleeves are held securely to the porcelain body. This insulating-piece can be molded in porcelain with a simple die, while all the metal parts 55 may be rapidly made with automatic machinery. The face-plate C is either cast or made from sheet metal, a recess being blanked and milled out for the lid D, which when down makes a finished surface and incloses all current-carrying parts when the temporary connection is withdrawn.

Fig. 3 is a sectional view of a smaller size of my improved coupling adapted for restricted spaces and to be used without fuses. The 65 construction of the receptacle B is exactly similar to that shown in Fig. 1. The face-plate is also similar, except in its outer contour, which is round.

The cap a, Figs. 3 and 4, is recessed at F 70 and provided with holes V V' for the line-wires or cable and with shouldered holes for the screw-plugs h h', which are threaded for a portion of their length and screw into the contact-plates r r', clamping the cable ends 75 between said plates and the bottom of the cap-recess.

What I claim as my invention, and desire to secure by Letters Patent, is—

1. In an electric coupling for making temporary connections to an electric circuit, as a new article of manufacture, the insulating-body B with shouldered recesses adapted to receive the metal sleeves S S' with the fastening-nuts J J' and wire-binding screws T T' in 85 combination with a face-plate and cap adapted to form the terminal of the temporary circuit.

2. In an electric coupling, an insulating-body provided with shouldered recesses, metal 90 sleeves mounted therein and having shoulders for engaging the shoulders of the recesses, nuts threaded on said sleeves for holding said shoulders in engagement, recesses in the ends of said sleeves for the wires, and 95 binding-screws threaded in said sleeves, substantially as described.

3. An insulating-body for an electric coupling provided with shouldered recesses adapted to receive metallic sleeves, and with slots 100

upon the sides opening into said recesses and adapted for binding-screws in the metallic sleeves, substantially as described.

4. In an electric coupling a cap *a* of insulating material recessed at *F* and provided with holes *V*, *V'* for the line-wires and with shouldered holes for the plugs, substantially as described.

5. In an electric coupling, a cap *a* recessed

at *F* and provided with shouldered holes opening into said recesses, screw-threaded plugs *h*, *h*, in said holes, plates in said recesses *F* threaded on said plugs and serving to clamp the line-wires, substantially as described.

NORMAN MARSHALL.
